UNITED STATES PATENT OFFICE

120,866

DESIGN FOR A VEHICLE HEATER

George R. Lippitt, Cleveland Heights, Ohio, assignor to Eaton Manufacturing Company, Cleveland, Ohio, a corporation of Ohio

Application May 22, 1939, Serial No. 85,128

Term of patent 7 years

To all whom it may concern:

Be it known that I, George R. Lippitt, a citizen of the United States, residing in Cleveland Heights, in the county of Cuyahoga, State of Ohio, have invented a new, original, and ornamental Design for a Vehicle Heater, of which the following is a specification, reference being had to the accompanying drawing, forming a part thereof, wherein:

Fig. 1 is a perspective view of a vehicle heater embodying my new design; and

Fig. 2 is a top plan view of the heater shown in Fig. 1; and

Fig. 3 is a side elevational view of the heater shown in Fig. 1 and taken on the right hand side thereof.

A view of the heater shown in Fig. 1 rotated through an angle of one hundred eighty degrees (180°) would be identical with the view shown in Fig. 1.

What I claim is:

The ornamental design for a vehicle heater, substantially as shown and described.

GEORGE R. LIPPITT.
